ACCORDION

Donald E. Noble, Chicago, Ill.

Application June 11, 1949, Serial No. 3,209

Term of patent 14 years

(Cl. D56—1)

To all whom it may concern:

Be it known that I, Donald E. Noble, a citizen of the United States, residing at Chicago, in the county of Cook and State of Illinois, have invented a new, original, and ornamental Design for an Accordion, of which the following is a specification, reference being had to the accompanying drawings forming a part thereof.

In the drawings:

Fig. 1 is a perspective view of an accordion showing my new design;

Fig. 2 is a side elevational view looking from the left-hand side of Fig. 1; and

Fig. 3 is a side elevational view looking from the right-hand side of Fig. 1.

The dominant features of my design reside in that portion shown in full lines in the drawing.

I claim:

The ornamental design for an accordion, as shown and described.

DONALD E. NOBLE.
